Primary Examiner—Adir Aronovich
Attorney, Agent, or Firm—Kelly Bauersfeld; Lowry & Kelley, LLP[57] **CLAIM**

The ornamental design for a dual function tool for staple removing and letter opening, as shown and described.

DESCRIPTION

FIG. 1 is a top, front and right side perspective view of a dual function tool for staple removing and letter opening, embodying my new design, wherein:

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof;

FIG. 8 is a top, front and right side perspective view of a second embodiment of the dual function tool for staple removing and letter opening, embodying my new design, wherein:

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.
